UNITED STATES PATENT OFFICE.

ALFRED STARKE, OF SCOTTDALE, PENNSYLVANIA, AND HANS VON WARTENBERG, OF DANZIG-LANGFUHR, FREE STATE OF DANZIG, ASSIGNEES TO THE FIRM OF OZON-HOCHFREQUENZ, G. M. B. H., OF BERLIN-WILMERSDORF, GERMANY.

PROCESS FOR PRODUCING OZONE.

Application filed February 2, 1923. Serial No. 616,620.

To all whom it may concern:

Be it known that we, ALFRED STARKE and HANS VON WARTENBERG, citizens of the Free State of Danzig, and residents, respectively, of Scottdale, in the county of Westmoreland and State of Pennsylvania, and of Langfuhr, near Danzig, in the Free State of Danzig, have invented certain new and useful Improvements in and Relating to a Process for Producing Ozone; and we do hereby declare the following to be a full, clear, and exact description of the invention, of which the following is a specification.

15 It has already been proposed to employ for the operation of ozone tubes instead of alternating currents of the usual frequency of 50 per second, alternating currents of higher frequency (see Warburg & Leithauser, Ann. Phys. (4) vol. 28, pp. 15, and 36, 1909), and it has been found that the use of high frequencies has the advantage that the current load and the efficiency are greater, although it has the drawback that 25 it reduces the maximum yield.

Let A_o denote the maximum yield in ozone (calculated in grammes per kilowatt-hour) which is attainable for a concentration 0 of ozone and the concentration of the 30 ozone be defined as being the ratio between the quantity of ozone and the quantity of the air subjected to ozonization in the apparatus. It has been found that when use is made of frequencies higher than 50 per second, the maximum yield A_o above referred to is reduced by a value ϵ which can only be found empirically, this value being dependent upon the frequency. As this reduction 35 is also dependent upon the concentration, the yield for a particular concentration c is expressed by the formula

$$A = A_o - \epsilon c$$

The formula has been tested up to 500 45 frequencies per second and the discovery has been utilized in practice, sometimes frequencies up to 700 having been reached. In the absence of experimental data capable of being used to explain the real mechanism 50 of ozonization, it is not possible to say beforehand what the effect would be if the frequency was considerably increased.

From the empiric data hitherto obtained, it may be expected that the ozone yield per

square unit of tube surface will be further 55 increased, but there is no indication as to how quickly this increase will take place, and whether it will only increase up to a maximum and then decrease again.

It has already been proposed to use high 60 frequency currents for producing ozone, the process consisting in employing a condenser connected in parallel with the ozonizer, a 65 sparking gap being interposed between the condenser and the ozonizer, and the circuit being tuned to the desired frequency.

As is well known, such a process produces only damped high frequency oscillations, the frequency being approximately 1 70 million per second. The efficiency of this 75 method of producing high frequency currents is naturally very low.

We have found by experiments carried out with undamped oscillations that a tube 80 consuming 1 watt at 50 periods, could be 75 loaded with 30 watts at 4000 periods, and with 100 watts at 8000 periods, without increasing the initial voltage and without the ozone yield dropping below the initial 85 amount of about 200 grammes of ozone per kw. hr. obtained from oxygen. That is to say, the ozonization could be carried out with a frequency 160 times higher than that of the usual frequency of 50 to obtain the same output 90 in an apparatus which is one hundred times smaller. A similar result was also obtained with larger tubes; in that case the temperature of the air or oxygen treated was suitably reduced by intensive cooling. In 95 practice it is preferable to use higher frequencies than those above referred to, viz, between 10,000 and 100,000 periods per second.

These experiments have shown that tubes 100 constructed in the usual manner, irrespective of whether one or both electrodes is or are made of glass, have the drawback that they are perforated in the case of a high load; in actual practice, frequently even in the case of a moderate load.

A powerful edge action (creeping sparks, silent discharges) and consequently heating and destruction of the glass, takes place at the ends of the electrodes. This drawback 105 may be avoided without impairing the working of the apparatus by thickening the dielectric at the edges of the solid dielectric, and by increasing the thickness of the layer

of gas, this thickening being effected within the cooling zone, and as regards both electrodes. Preferably the thickening is such that the ionizing voltage is no longer attained in the thickened part with the given working voltage of the ozonizer. As the edge action consumes energy, the arrangement just referred to will increase the output of the ozonizer.

10 The accompanying drawing illustrates one form of apparatus for carrying the present invention into effect.

The ozonizer comprises three concentric chambers separated from one another and 15 provided with the corresponding inlets and outlets.

5 is the inner electrode which consists in a known manner of a tube of glass or like material capable of acting as a dielectric and 20 of a wire coil or wire netting carried by the said tube. This form of construction of electrodes being well known, it is not considered necessary to illustrate the actual construction. Water is caused to flow through 25 the electrode 5 which for this purpose is provided with an inlet 7 and an outlet 9.

11 is the outer electrode which similarly consists of a glass or like tube and of a wire coil or wire netting provided thereon. The 30 outer and the inner electrode thus enclose a cylindrical space 6 which is provided with an inlet 8 and an outlet 10. The glass tubes of the two electrodes are preferably fused together at the lower and upper ends.

35 1 is a cylinder preferably of glass which surrounds the upper electrode and is closed up by packings 13 and 14 which make a tight joint with the electrode tubes. 2 is a water inlet and 3 a water outlet provided for the 40 annular chamber 12 which is formed between the outer electrode 11 and the cylinder 1.

During the operation of the ozonizer, 45 water which is in electrical connection with the one pole of the source of electricity is admitted through the pipe 2 whilst water, which is in electrical connection with the other pole of the source of electricity is admitted through the pipe 7 to the annular 50 chamber 12 and the hollow space of the elec-

trode 5 respectively, the water leaving the said hollow spaces at 3 and 9 respectively. The air or oxygen to be ozonized is admitted at the inlet 8 into the space 6 in which the electric discharges take place between the electrodes which are at different potentials.

It is known in apparatus for the production of ozone by means of electrical effluvia gradually to increase the gas gap between two tubular metal electrodes at the edges thereof by bending the outer and inner electrodes outwardly and inwardly respectively, in order to increase the electric resistance at these points, and we wish it to be understood that the ozonizer according to the present invention is limited to its use with high frequency currents between 10,000 and 100,000 periods per second and in combination with means for ensuring that the ends of both electrodes shall be subjected to a cooling action that is sufficiently strong for high frequency currents.

What we claim is:-

1. In a process for producing ozone in an ozonizer having electrodes, which consists in passing the medium to be ozonized through the ozonizer between the electrodes and subjecting it therein to the action of electric energy in the form of alternating currents, supplying the alternating currents to the said electrodes in the form of undamped oscillations, the periodicities of which lie in the range from 1,000 to 100,000 periods per second as set forth.

2. An ozonizer for the electric production of ozone by means of high frequency alternating currents comprising a tubular electrode, another tubular electrode surrounding the same in combination with a dielectric between the said electrodes the dielectric being thicker at the ends of the electrodes as compared with its portion between the ends thereof and the said electrodes being capable of exerting at the said ends where the thicker dielectric is provided, a strong cooling action as regards high frequency currents.

In testimony whereof we have signed our names to this specification.

ALFRED STARKE.

HANS von WARTENBERG.
